GARMENT HANGER

Cordell C. Light, Amarillo, Tex., assignor of fifty
per cent to Tyra P. Byrum, Amarillo, Tex.

Application August 1, 1949, Serial No. 107,957

1 Claim. (Cl. 223—91)

1

This invention relates to an attachment for a wire clothes hanger primarily designed for suspending skirts and pants.

The primary object of this invention is to provide an attachment of the character described which is so constructed that it can be readily secured upon and removed from the conventional wire hanger with a minimum of time and effort.

A further object of this invention is to provide a skirt and pants attachment for a wire hanger which is relatively simple in design and construction, cheap to manufacture in large quantities, easy to assemble and support upon a wire hanger, and extremely efficient for its intended purpose.

Yet another object of this invention is to provide in a wire clothes hanger, an attachment for suspending skirts and pants comprising a first plate, means for removably suspending said first plate upon the hanger, a second plate, means for movably attaching said second plate to said first plate, and spring means interposed between the plates adjacent their top edges normally urging the bottom edges of said plates together in clamping position.

These, together with various ancillary objects and features of the invention which will later become apparent that the following description proceeds, are attained by the device a preferred embodiment of which has been illustrated by way of example only in the accompanying drawings, wherein:

Figure 1 is a perspective view of the attachment shown secured to a conventional wire hanger;

Figure 2 is a sectional view taken substantially on the plane of section line 2—2 of Figure 1;

Figure 3 is a fragmentary end elevational view of the attachment illustrating the manner of moveably suspending one of the plates on the other; and,

Figure 4 is a fragmentary perspective view of the top portion of one of the plates.

Specific reference is now made to the drawings. In the several views in the accompanying drawings and in the following specification reference characters indicate corresponding elements throughout.

The device of the instant invention is generally indicated at 10 and is to be removably supported upon a conventional wire hanger 12 having a neck portion 14 and a horizontal bar 16. The attachment 10 comprises a first plate 18 and a similarly shaped second plate 20 which may be fabricated

of suitable light weight materials, such as plastics, aluminum, and other light weight metals.

The first plate 18 is provided with inclined edges 22 adjacent the top thereof, the edges being inclined at the same angle and in the same direction as the shoulder bars of the wire hanger 12 so that a coat or other garment may be suspended upon the wire hanger with the attachment thereon in the conventional manner. The top edge of the first plate 18 includes a down-turned lip 24 which includes a longitudinal slot 26 for receiving the neck portion 14 of the wire hanger. The bottom edge of the first plate 18 is provided with an upturned longitudinal lip 26 for receiving and gripping the horizontal bar 16 of the wire hanger 12.

Adjacent the corners 28 of the first plate are transversely extending bolts 30 which are secured to the first plate in any suitable manner. It is preferred that one end of the bolt 30 be threaded and received in threaded apertures in the first plate and nuts 32 be received on the bolts for securely attaching the same to the first plate as will be readily apparent from the drawings. The second plate 20 is of the same dimensions and configuration as the first plate and includes a down-turned lip 34 at its top end and an upturned, longitudinal lip 36 at its bottom end. Adjacent the corners 38 of the second plate 20, the latter is provided with apertures 40 for slidably receiving the bolts 30 so that the second plate 20 is movably relative to the first plate 18. The free ends of the bolts 30 carry nuts 42 for limiting the outward movement of the second plate 20 relative to the first plate 18.

Interposed between the two plates adjacent the top edges is a coil spring 44 which is secured as at 46 and 48 by means of rivets to the first and second plates. This coil spring normally urges the top ends or edges of the two plates apart and thereby urges the bottom edge 36 of the second plate towards and in gripping engagement with the bottom edge of the first plate, as will be clearly understood with reference to Figure 2.

In use, the attachment 10 is suspended upon the hanger 12 by passing the neck portion 14 of the wire hanger through the slot 26 on the top edge of the first plate 18. Thereafter, the horizontal bar 16 of the wire hanger is flexed or bent upwardly until it clears the free edge of the lip 26 and slips into the lip as shown in the drawings. Skirts and pants are suspended on the attachment by compressing the second plate at the lip portion 34 thereof against the action of the spring to urge the bottom edge 36 of the second

plate 20 away from the bottom edge of the first plate. The skirts and pants are positioned between the plates at their bottom edges and a release of the second plate will allow the skirts and pants to be gripped between the bottom edges of the first and second plate. To remove the attachment from the hanger, the horizontal bar 16 is flexed or bent upwardly to clear the free edge of the lip 26 and then the attachment is removed through the neck of the hanger as will be readily understood.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

In a wire clothes hanger, an attachment for

5 suspending skirts and pants comprising a first vertical plate having a lip at its upper end, said lip including a slot for loosely embracing the neck of the hanger and an upturned longitudinal lip at its lower end for receiving the horizontal bar of the hanger, a second vertical plate of the same dimensions as the first plate, bolts carried by said first plate slidably extending through said second plate, nuts on the free ends of said bolts for limiting the outward movement of said second plate, and a spring interposed between and terminally secured to said plates adjacent their upper ends normally urging the lower ends of said plates together into clamping position.
